UNITED STATES PATENT OFFICE.

HENRY PHELPS GAGE AND EMILIO PASCUCCI, OF CORNING, NEW YORK, ASSIGNEES TO CORNING GLASS WORKS, A CORPORATION OF NEW YORK.

DESIGN FOR A REFRACTING COVER-GLASS.

52,437.

Specification for Design.

Patented Sept. 17, 1918.

Application filed October 18, 1917. Serial No. 197,344. Term of patent 14 years.

To all whom it may concern:

Be it known that we, **HENRY PHELPS GAGE** and **EMILIO PASCUCCI**, citizens of the United States, residing at Corning, in the county of Steuben and State of New York, have invented a new, original, and ornamental Design for Refracting Cover-Glasses, of which the following is a specification, reference being had to the accompanying drawing, forming part thereof.

The figure is a plan view of a refracting

cover glass having our new design applied thereto.

We claim:

The ornamental design for a refracting cover glass as shown.

HENRY PHELPS GAGE.
EMILIO PASCUCCI.
